(57) **CLAIM**

The ornamental design for a radiation shielding container portion, as shown and described.

DESCRIPTION

FIG. 1 is a perspective view of a radiation shielding container portion;

FIG. 2 is a top plan view thereof;

FIG. 3 is a cross section view thereof taken along line 3—3 in FIG. 2;

FIG. 4 is a cross section view thereof taken along line 4—4 in FIG. 2;

FIG. 5 is a front elevation view thereof;

FIG. 6 is a side elevation view thereof; and,

FIG. 7 is a rear elevation view thereof.

The broken lines shown in the figures illustrate portions of the radiation shielding container portion that form no part of the claimed design.
